UNITED STATES PATENT OFFICE.

HENRY ARTHUR PAGE, OF RICHMOND, VIRGINIA.

DESIGN FOR AN ILLUMINATED SEAT INDICATOR FOR AUDITORIUMS AND THE LIKE.

Application filed December 3, 1921. Serial No. 519,779. Term of patent 3½ years.

To all whom it may concern:

Be it known that I, HENRY ARTHUR PAGE, a citizen of the United States, residing at Richmond, in the county of Henrico and State of Virginia, have invented a new, original, and ornamental Design for Illuminated Seat Indicator for Auditoriums and the like, of which the following is a specification, reference being had to the accompanying drawing, forming a part thereof.

The figure is a perspective view of an illuminated seat indicator, showing my new design.

I claim:

The ornamental design for an illuminated seat indicator for auditoriums and the like, as shown.

HENRY ARTHUR PAGE.
